UNITED STATES PATENT OFFICE.

TOBIAS HAMILTON, OF CENTREFIELD, OHIO, ASSIGNOR OF ONE-HALF TO
SAMUEL SOLLARS, OF SAME PLACE.

FIRE-ESCAPE.

SPECIFICATION forming part of Letters Patent No. 309,619, dated December 23, 1884.

Application filed October 27, 1884. (No model.)

To all whom it may concern:

Be it known that I, TOBIAS HAMILTON, a citizen of the United States, residing at Centrefield, in the county of Highland and State of Ohio, have invented a new and useful Improvement in Fire-Escapes, of which the following is a specification, reference being had to the accompanying drawings.

My invention relates to fire-escapes; and it has for its object to provide a device of this character which shall be thoroughly fire-proof, thus insuring to the occupants of a building a safe descent.

A further object of the invention is to furnish a fire-escape which shall be cheap and simple in its construction, and to provide such escape with a tunnel, whereby persons escaping from a burning building will be protected from the falling timbers and other material.

With these ends in view the invention consists in a tower constructed of brick, stone, or like material, an inner tower or casing separated from the outer tower by an air-space, doors arranged to connect with said inner casing at each story, and a suitably-arranged tunnel.

The invention further consists in the improved construction and combinations of parts hereinafter fully described, and pointed out in the claims.

In the drawings, Figure 1 is an elevation of a building provided with my improved escape. Fig. 2 is a horizontal section on the line $\alpha\alpha$ of Fig. 1.

In the accompanying drawings, in which like letters of reference indicate corresponding parts in all the figures, A represents a building, and B my improved escape connected therewith. This escape consists of a tower which extends the entire height of the building, and is preferably constructed of brick or stone. Arranged concentrically within the outer tower is a tower preferably constructed of iron plates riveted together. A space, D, is left between the inner tower, C, and the outer tower, B.

E represents a shaft, which is arranged within the inner tower, C, and extends from the top to the bottom of the same. A spiral

staircase is secured to said shaft and to the inner side of the inner tower, said staircase extending from top to bottom. Said staircase F is equipped with a railing, a, which is attached to the shaft E. At each story of the building is a door communicating with the air-chamber between the inner and outer towers.

G represents series of rooms which are formed between the inner and outer towers at each story of the building. These rooms are air-tight, and have no communication with the air-chamber. A door is provided in each of these rooms, which communicates with the stairway in the inner casing or tower. The doors communicating with these rooms are equipped with springs or weights, in order that they will always be kept closed. The bottom of these series of rooms formed in the air-chamber at each story of the building has communication with the interior of the tower, and communicates with a passage or tunnel leading to some point at a distance from the burning building.

It will be seen that with my improved escape the descent may be made without any danger, that the structure is thoroughly fire-proof, and that by the employment of a tunnel, as described, there will be no possible chance of persons being struck by falling timbers. It will also be seen that an escape constructed as above described is simple and durable.

Having fully described my invention, what I claim as new, and desire to secure by Letters Patent, is—

1. A fire-escape tower consisting of an inner and an outer structure extending from the top to the bottom of a building and leaving an air-space between them, substantially as set forth.

2. A fire-escape consisting of an inner and an outer tower arranged to leave an air-space between them, a spiral staircase in said inner tower, and air-tight passage-ways communicating with said inner tower, substantially as set forth.

3. A fire-escape consisting of an outer tower of brick or stone and inner tower of iron arranged to leave an air-space between them, 100

air-tight rooms formed in said space at each landing, and having communication with both the inner tower and the building, substantially as set forth.

5 4. A fire-escape consisting of an inner and an outer tower arranged to leave an air-space between them, and a tunnel having communication with the inner tower at its lower end by means of a passage in the air-space be-

tween the two towers, substantially as set forth.

In testimony that I claim the foregoing as my own I have hereto affixed my signature in presence of two witnesses.

TOBIAS HAMILTON.

Witnesses:

A. HARRIS,
LEWIS PFISTER.
